(No Model.)

J. BRADY.

KEY LEVER FOR TYPE WRITING MACHINES.

No. 417,626.

Patented Dec. 17, 1889.

Fig. 1.

Fig. 2.

UNITED STATES PATENT OFFICE.

JAMES BRADY, OF BROOKLYN, NEW YORK, ASSIGNOR TO THE FITCH TYPE WRITER COMPANY, OF DES MOINES, IOWA.

KEY-LEVER FOR TYPE-WRITING MACHINES.

SPECIFICATION forming part of Letters Patent No. 417,626, dated December 17, 1889.

Application filed July 19, 1888. Serial No. 280,362. (No model.)

To all whom it may concern:

Be it known that I, JAMES BRADY, a citizen of the United States, residing at Brooklyn, in the county of Kings and State of New York, have invented new and useful Improvements in Key-Levers for Type-Writing Machines, of which the following is a specification.

My invention relates to type-writing machines, and the purpose thereof is to provide a novel construction of the key-levers used therein, whereby the cost of manufacturing such parts is very materially reduced, while the strength and simplicity thereof are correspondingly promoted. It is also my purpose to provide an extremely simple construction whereby the keys or finger-pieces, with their proper symbols, may be securely mounted upon the key-bars in such manner that they may be detached therefrom at any time, if necessary, and shall have, when in use, a broad base of support and a firm and permanent connection with the extremities of the key-bars. It is my further purpose, also, to provide a simple and inexpensive construction of the key-bars, whereby the links connecting the said key-bars to the type-carrying arms may be readily and instantaneously attached to and detached from the same, a firm and secure pivotal connection being provided between said key-bars and link when said parts are connected. It is my purpose, also, to provide a key-bar formed from a single integral piece of metal, having a bearing between its ends adapted to engage with a straight shaft, and provided with an extended bearing to support and guide the key-bar and resist any tendency to lateral or torsional displacement. It is my purpose, finally, to apply my invention to the key-bars of typewriters already in use without material change in the form and construction of said parts; and to the several ends mentioned the invention consists in the novel features of construction and new combinations of parts hereinafter fully described, and then definitely pointed out in the claims.

Referring to the drawings accompanying this application, Figure 1 is a side elevation of a key-bar constructed in accordance with my invention, showing the key-bar as it ap-

pears after it has come from the dies, but before it is completed. Fig. 2 is a perspective view of the key-bar shown in Fig. 1 when completed, together with part of the link to 55 which said arm is pivotally connected. Fig. 3 is a central vertical section of the key or finger-piece mounted upon the completed key-bar. Fig. 4 is a bottom plan view of the parts shown in Fig. 3. Fig. 5 is a side elevation of the rearward end of the completed key-bar, showing the manner of attaching and detaching the link which connects said key-bar to the type-carrying arm. Fig. 6 is a rear end elevation of the parts shown in Fig. 5. 65 Fig. 7 is a side elevation of the completed key-bar with the link attached as the parts appear when in use. Fig. 8 is a plan view of one of the completed key-bars. Fig. 9 is a side elevation of a key-bar of ordinary or known 7c form, showing the construction by which the present invention is incorporated therein.

In the said drawings, the reference-number 1 designates the body portion of a key-bar constructed in accordance with my invention. I form these key-bars, preferably, of flat metal, which may be struck in a die and turned out in a single blank at one blow of the die. This blank consists of the body portion 1, having a bearing 2 between its ends 80 to receive the supporting-shaft, and provided with the upwardly-turned extremity 3, upon which the key or finger-piece is to be mounted. At or near the angle between the body portion 1 and the vertical part 3 is formed a vertical extension 4, which is adapted to serve as a guide for the key-bar in its vertical movements and by its broadened surface to resist any tendency to torsional displacement of the keys. At the rearward end of the key-bar the metal is widened and is divided by two parallel cuts into three horizontal sections 5, 6, and 7, whereof the middle section 6 may, if desired, be slightly wider than the others. At the upper extremity of the vertical portion 3 is formed a substantially circular enlargement 8, having a vertical slot or cut 9, extending from its upper edge to the center of the circular part 8. 95

In completing the key from the blank shown 100 in Fig. 1 I bend the divided portions of the circular enlargement 8 in opposite directions

and upon a diametrical line drawn through the center at right angles to the slot 9, thereby forming two quadrantal horizontal plates 12, Fig. 2, lying upon opposite sides of the 5 upright arm 3. Upon these plates I mount the key, consisting of a circular shell 13, having its upper edge 14 spun inward and downward and provided with lugs 15, depending from its lower edge upon opposite sides, sub- 10 stantially as shown in Fig. 4. The glass pro- 15 tector-plate 16 is laid within the circular shell 13, resting against the spun-down edge, 14. The plate, card, or paper 17, having the proper symbol, is then laid beneath the glass, 20 and the whole is placed upon the quadrantal plates 12, where the parts are secured by simply bending the lugs 15 inward and upward, two of said lugs being brought into engagement with the horizontal plates 12, and 25 the others being bent up against the letter plate or card 17. These lugs, lying upon opposite sides of the vertical arm 3, serve to prevent the finger-piece from turning upon its support. Between the ends of the key- 30 bar is formed the bearing 2 for the supporting-shaft, the bar being suitably widened for the purpose. Upon one side of the bar, arranged centrally in the widened part, is formed the tubular bearing 18, which may be 35 attached thereon, or, if preferred, may be struck up by the die when the blank is formed and finished afterward.

Inasmuch as the key-bars when mounted are all supported upon a straight shaft, and 35 as the ends carrying the keys or finger-pieces diverge or spread outward in fan shape from the rearward extremities, to which the links are connected, to the forward ends, on which the keys are mounted, it is necessary to so 40 form the several bars that the axes of the bearings 18 shall be arranged at different angles to the vertical planes of the several key-bars, said angles being proportioned to the angles of divergence of the key-bars. I there- 45 fore form upon each side of the widened bearing portion a bend 19, Fig. 8, whereby the part carrying the tubular bearing 18 is brought into parallelism with the corresponding portions of the other keys, while those por- 50 tions of the key-bar upon each side thereof lie in substantially one and the same plane and form the proper angle with the shaft lying in the bearing 18.

Upon the central section 6 of the threefold 55 rearward extremity of the key-bar is mounted in any suitable manner a pivot-pin 20, projecting at right angles from one face of said central section. The upper and lower sections 5 and 7 are then bent slightly in the 60 same direction and the central section is bent to a corresponding degree in the opposite direction to bring the parts into substantial parallelism, as shown in Figs. 2 and 6. The link connected to said key-bar is provided at 65 its end with a plate 21, having a width which enables it to pass between the sections 5 and 7, and, when held horizontally and provided

with an aperture 22, adapted to engage the pivot-pin 20. When this engagement is effected, the link is turned upon the pivot-pin 70 until it stands at the proper angle with the key-bar, in which position it is held in its said engagement by the sections 5 and 7, as shown in Figs. 5, 6, and 7. Its disengagement is effected by turning the link until the plate 75 21 is parallel with the cleft sections upon the end of the key-bar, whereupon it may be readily removed from the pin.

I have shown the link as composed of a bar 80 23, tapped into an eye upon the end of the plate 20, as this construction gives a convenient vertical adjustment and has been used heretofore in type-writers; but I may construct said link in any other suitable manner.

In many of the type-writers now in use the 85 key-bars are mounted upon their supporting-shaft at their rearward extremities, while the links are connected thereto at a point intermediate of the ends. To adapt my invention to machines of this class, I may form the shaft-bearing 24 at the end of the key-bar, Fig. 9, and at a suitable point between the extremities form the connecting parts 25. In this construction I simply extend the key-bar in width sufficiently to enable the said arms 25 to be 90 formed above and below the same and integrally therewith and mount the pivot-pin 26 upon the body of the key. In this construction, also, the sections 25 only are bent laterally to admit the link, the body of the key 100 being substantially straight. The manner of attaching and removing the link is the same as that already described.

Although this invention has been described as adapted to a type-writer, it is evident that 105 it may be used without material alteration in apparatus of various kinds.

What I claim is—

1. A key-bar for type-writers, consisting of a metallic plate having an upwardly-turned end provided with a centrally-slotted extension, the metal on each side of the slot being bent in opposite directions at right angles to said slot, forming two horizontal quadrantal plates to support the key or finger-piece, substantially as described.

2. A key-bar for type-writers, consisting of a flat metallic plate having an upwardly-turned end provided with a circular enlargement having a central slot, the metal on each side of the slot being bent at right angles thereto and in opposite directions, in combination with a circular shell containing the glass protector-plate and letter-card, said shell having depending lugs bent upward to engage the key-bar and support the glass and card, substantially as described.

3. A key-bar for type-writers, composed of a flat metallic plate having at the point where the link is connected therewith three parallel 130 sections or parts, said parts being spread laterally, but retained in substantial parallelism, and the central section having a pivot-pin to engage the link, substantially as described.

4. A key-bar for type-writers, composed of a plate having its rearward extremity cleft into three parallel sections spread laterally, but preserved in essential parallelism, the 5 central section having a pivot-pin projecting toward the two parallel sections, substantially as described.

5. In a type-writer, a key-bar consisting of an integral metallic plate having an upwardly-10 extending forward extremity to receive the key or finger-piece, and provided at or near the foot of said vertical portion with a vertical extension 4 to serve as a guide and resist torsional displacement, substantially as de-15 scribed.

6. A key-bar composed of a flat metallic plate having the vertical portion 3, provided with the centrally-cleft circular enlargement 8, having a key 13 mounted thereon, and hav-20 ing, also, the rearward extremity cleft to form the three sections 5, 6, and 7, in combination with the link 23, pivotally connected with one of said sections, substantially as described.

7. In a type-writer, the combination, with a key-bar having a flat metallic body pro-25 vided at the point of attachment of the link with three substantially parallel arms or sections, with a pivot-pin mounted upon one face of the central section, of a link having a flat end provided with an aperture adapted to en-30 gage said pivot-pin, said flat end being so formed as to pass between the upper and lower parallel sections of the key-bar when laid horizontally on the central section, and to be then turned at an angle to the key-bar 35 to engage the upper and lower sections, by which the pivotal engagement is preserved, substantially as described.

In testimony whereof I have affixed my signature in presence of two witnesses.

JAMES BRADY.
